(57) **CLAIM**

The ornamental design for a appliance display unit, as shown and described.

DESCRIPTION

FIG. 1 is a front view of an appliance display unit showing my new design;

FIG. 2 is a top perspective view of FIG. 1;

FIG. 3 is an enlarged right side view of FIG. 1;

FIG. 4 is a top perspective view of FIG. 1 shown in a partially extended position;

FIG. 5 is a top perspective view of FIG. 1 shown in a fully extended position;

FIG. 6 is a top perspective view of FIG. 1 shown in a left facing fully extended position; and,

FIG. 7 is a top perspective view of FIG. 1 shown in a right facing fully extended position.

The broken lines shown in the drawing disclosure are for illustrative purposes only and form no part of the claimed design.
